ATTORNEY

UNITED STATES PATENT OFFICE.

JAMES WALLACE, OF OAKLAND, CALIFORNIA.

THEATER AND LIKE CHAIR.

1,145,340.

Specification of Letters Patent.

Patented July 6, 1915.

Application filed May 20, 1914. Serial No. 839,781.

To all whom it may concern:

Be it known that I, JAMES WALLACE, a citizen of the United States, residing at Oakland, in the county of Alameda and State of California, have invented new and useful Improvements in Theater and like Chairs, of which the following is a specification.

This invention relates to folding chairs, and more particularly to that class of chairs which is used in theaters and other public assembly rooms.

It is one of the objects of the present invention to provide a simple, substantial, cheaply manufactured chair of the character described, which is especially adapted for installation and use in places where the seats are liable to be crowded and where the audience is ever and continuously changing; *i. e.*, a seat which can be quickly and easily raised by the occupant to make aisle space when a person desires to pass.

Another object of the invention is to provide a seat which is so constructed that any number of same may be arranged in the form of a semicircle, or the like, without cramping the pivotal connections of the seat or interfering with the free working of same.

Further objects will hereinafter appear. The invention consists of the parts and the construction and combination of parts as hereinafter more fully described and claimed, having reference to the accompanying drawings, in which—

Figure 1 is a side elevation of the chair showing the seat in lowered position. Fig. 2 is a similar view showing the seat in the raised position. Fig. 3 is a plan view, partly in section, showing a number of seats connected in the form of a semicircle. Fig. 4 is a detail perspective view of plate 4. Fig. 5 is a cross section of the seat frame showing the plate 4 in plan view.

Referring to the drawings, A indicates the standards or side frames of the seat, between which the back sections are secured, as at 2. The side frames are substantially T-shape in cross section, and the front edge of each frame is provided with laterally extending lugs 3, one pair of lugs being formed on each side of the frame. Pivots mounted in each pair of lugs is a plate 4 and mounted at one side of each plate is a pivot member 5, a stop 6, and a set-screw 7.

The seat proper, indicated at 8, is secured

to a pair of bracket plates 9 which in turn are carried by the plates 4 and pivots 5. Each bracket plate is extended to form a pair of stops 10 and 11, one to limit the upward movement of the seat and the other to support the seat in the lowered position. Projecting from one side of each bracket plate 9 is a pivot pin 10', and connecting said pin with the arm of the chair, indicated at 13, is a link 14 which projects through and is guided in a slot 14^a formed in the frame A. The arms are in this instance pivotally connected, as at 15, to the back of the seat frame. The link connection between the arms and the seat provides a means by which the seat may be raised or lowered through means of the arms 13. The pivotal mounting of the arms, together with link connections between same and the seat, is of great importance as it greatly increases the utility of the chair, especially in theaters and like places where the seats are liable to be crowded and where the audience is ever and continuously changing.

The occupant of a chair has a natural tendency to place the hands on the extremities of the arms of the chair and they are thus in a natural position to grasp and raise same, when standing up to make aisle space for passing persons. The occupant is thus entirely relieved of stooping down and grasping the front edge of the seat.

Another important feature of the present invention is the provision of the pivotally mounted plates 4 in which the seat proper is supported. These permit the seats to be arranged in a semi-circle, or the like, without crowding the pivotal connections or interfering with the free working of the seats. When arranging the seats in a semicircle, as indicated in Fig. 3, it is only necessary to adjust the set-screws 7 in such a manner that they will hold the plates 4 at a slight angle, as indicated at 16, with relation to the seat frame. A number of chairs may thus be arranged in practically any shape without interfering with the free working of the seat.

The bracket plates 9 are slotted, as at 17, to permit adjustment between the seat proper and the bracket plate. This, together with the pivotal mounting of the plates 4, permits the seats to be removed at any time without interfering with the main frames A or the back portions of the seats.

Secured to the front frame, by a screw

18, or similar means, on each side of the frame between the lugs 3, is a pair of angle plates 19. These are provided for the purpose of preventing the seat, with connected plates 4, from being lifted out of engagement with the lugs 3.

The materials and finish of the several parts of the chair are such as the experience and judgment of the manufacturer may 10 dictate.

Various changes in form, proportions and minor details of construction may be resorted to within the scope of the appended claims and I do not wish to limit myself 15 to the specific design and construction here shown.

Having thus described my invention, what I claim and desire to secure by Letters Patent is—

20 1. In combination with a chair frame having a back, and a seat pivoted to the frame, arms pivoted to the frame, and links pivoted to the arms and pivoted to the seat at points at a distance below the pivotal 25 points of the seat but closely adjacent the seat pivotal points whereby the seat may be raised up by but slight up movement of the arms and which movement of the arms causes same to extend at but slightly less 30 than a right angle to the back.

2. In combination, a chair frame, a plate

pivots connected thereto for movement about a vertical axis, a seat, a bracket secured to the seat and formed with an opening, a fixed pin projecting laterally from 35 the pivotal plate and freely engaging in the opening of the bracket whereby relative separable movement between the latter and plate will dislodge the bracket from the pin, and adjustable means for holding the plate 40 positively in an adjusted position against movement tending to separate the latter from the bracket.

3. In combination, a chair including spaced frames, a plate pivoted to each frame 45 for movement about a vertical axis and arranged to oppose the plate of the other frame, a pin projecting from each plate toward the other plate, a seat including means freely receiving the opposing pins whereby 50 on separable movement between the pins the seat will be dislodged, and screw means carried by the plates and adapted to engage with the frames for holding the plates against swinging movement from the seat. 55

In testimony whereof I have hereunto set my hand in the presence of two subscribing witnesses.

JAMES WALLACE.
